UNITED STATES PATENT OFFICE

119,967

DESIGN FOR A TOY BANK

Albert E. Sierad, Larchmont, N. Y., assignor to
George W. Button Corporation, New York,
N. Y., a corporation of New York

Application October 23, 1939, Serial No. 87,824

Term of patent 7 years

To all whom it may concern:

Be it known that I, Albert E. Sierad, a citizen of the United States, residing at 7 Barnum Road, Larchmont, in the county of Westchester and State of New York, have invented a new, original, and ornamental Design for a Toy Bank, of which the following is a specification, reference being had to the accompanying drawing, forming part thereof.

In the drawing:
Fig. 1 is a bottom plan view of a toy bank showing my new design.

Fig. 2 is a side elevation thereof.

Fig. 3 is a front view.

I claim:

The ornamental design for a toy bank, as shown.

ALBERT E. SIERAD.
